J. W. STEVENS.

CARBURETER.

APPLICATION FILED DEC. 15, 1913.

1,184,888.

Patented May 30, 1916.

UNITED STATES PATENT OFFICE.

JOHN W. STEVENS, OF ST. PAUL, MINNESOTA.

CARBURETER.

1,184,888.

Specification of Letters Patent. Patented May 30, 1916.

Application filed December 15, 1913. Serial No. 806,696.

To all whom it may concern:

Be it known that I, JOHN W. STEVENS, a citizen of the United States, resident of St. Paul, county of Ramsey, State of Minnesota, have invented certain new and useful Improvements in Carbureters, of which the following is a specification.

The object of my invention is to provide a carbureter having an air control which can be regulated from the driver's seat, and dispensing with fluttering or vibrating parts and the separate throttle valve usually provided in a carbureter of the ordinary type.

A further object is to provide a carbureter which will admit a specific and predetermined volume of air and having means within the control of the driver for increasing the volume of air admitted, according to atmospheric conditions and the speed required.

Other objects of the invention will appear from the following detailed description.

The invention consists generally in various constructions and combinations, all as hereinafter described and particularly pointed out in the claims.

In the accompanying drawings forming part of this specification, Figure 1 is a vertical sectional view through a carbureter embodying my invention, Fig. 2 is a similar view on a section line at right angles substantially to the section line of Fig. 1. Fig. 3 is a side view of that portion of the carbureter which controls the admission of air to the mixing chamber, Fig. 4 is a sectional view on the line $x-x$ of Fig. 3, Fig. 5 is a detail sectional view illustrating a modified construction.

In the drawing, 2 represents a casing having a fuel chamber or reservoir 3 communicating through a passage 4 and a valve 5 with a source of fuel supply (not shown).

The movement of the valve is controlled by the usual float 6, which encircles an inner casing or shell 7 between which and the walls of the casing 2 the reservoir 3 is formed. The casing 2 has a removable top 8 allowing access to a chamber 9 within the casing 7 through the open top 10 of said chamber. From this chamber a passage 11 leads to the engine cylinders (not shown).

In the base of the casing 7 is a fuel passage 12 communicating with the chamber 3 and with a nozzle 13 which projects up into the chamber 9 and is provided with a needle

valve 14 by means of which the flow of fuel through the nozzle is controlled in the usual way. Within the casing 7 I provide a cylindrical member 15 having an annular flange 16 that is seated in the wall of the casing 7 near the middle portion thereof and separates the lower portion of this chamber from the upper portion thereof. This cylinder is provided below said flange 16 with ports 17, shown extending vertically in the wall of the cylinder at intervals in the surface thereof and spaced apart and communicating with the lower portion of the chamber 9 and with the open air through the passage 7. Above the flange 16 ports 18 are provided. Fitting within the cylinder 15 is a hollow member 19 preferably in the form of a truncated cone, having a flange 20 which is seated against the lower end of the cylinder 15, the nozzle 13 projecting upwardly into said member and terminating beneath and near ports 21 provided in the upper portion of said member. The cylinder 15 and the member 19 are normally stationary, and the ports 21 in the member 19 are fixed in size and admit the mixture of air and fuel into the space inclosed by the cylinder 15.

Within the stationary cylinder 15 is a movable valve cylinder 22 shown as supported by the flange 20 and having ports 23 above the flange 16 and ports 24 below the flange 16 adapted to register respectively with the ports in the cylinder 15. The cylinder 22 has a stem 25 thereon provided with a lever 26 that is actuated by an arm 27 on a rock shaft 28 that is operated through a suitable mechanism extending to the driver's seat. This inner cylinder constitutes in effect the throttle of the engine, for by rotating it the driver can increase or decrease the area of the air ports in the cylinder 15 according to atmospheric conditions or the load on the engine. A stop pin 29 may be provided in the rotating inner cylinder for limiting its movement in both directions. The ports 18 are approximately equal in area to the combined area of the ports 17 and 21 and are so arranged that the ports 18 may, when partially opened, be equal substantially in area to the ports 21. When this relation exists between the ports 18 and 21, the ports 17 below the flange 16 will be entirely closed and the air currents then flow up through the ports 21 and out through the passages in the ports 18 on the

way to the engine cylinders. When, therefore, it is desired to reduce the supply of air, the valve cylinder is rotated until the ports 17 are fully closed and the air passing through the ports 21 and 18 will carry the fuel from the supply nozzle, and the openings of the ports 18 being substantially equal to the ports 21, the flow of air through them will not be retarded.

- 10 In case it is desired to increase the supply of air, the valve cylinder is rotated in the opposite direction, increasing the openings through the ports 18 and exposing additional openings through the port 17 sufficient to admit the desired increase in air volume. As the ports 17 are opened, a correspondingly greater area of the ports 18 will be exposed, so that as the air intake openings are increased in area to admit a 20 greater volume of air to the chamber within the cylinders, a correspondingly larger area of the ports 18 will be exposed to accommodate this increased volume of air, and a perfect ratio will be maintained at all 25 times in the operation of the carbureter. In this way a supply of fuel and air through the carbureter can be regulated by the driver, according to the speed of the engine desired and the atmospheric conditions.
- 30 That portion of the cylinder valve below the flange 16 will have the function of the auxiliary air intake of an ordinary carbureter, which usually becomes operative under increased suction and higher speed of 35 the engine.

In Fig. 5 I have shown a modified construction in which an outer cylinder 30 is provided, having a supporting flange corresponding to the one heretofore described 40 and telescoping with a cylinder 31 that is reciprocated through the operation of a link 32 from a suitable means. These cylinders are provided with upper and lower groups 45 of ports 33, 34, 35 and 36, the ports in the stationary member 30 being opened or closed with the movement of the reciprocating cylinder member 31. In other respects the 50 operation of this form of carbureter is the same as described above, the stationary or outer cylinder having the inwardly projecting, preferably cone-shaped, member provided with ports therein corresponding to those described with reference to Figs. 1 and 2.

55 In various ways the details of construction herein shown and described may be modified and still be within the scope of my invention.

I claim as my invention:

- 60 1. A carbureter comprising a casing having a chamber formed therein provided with air inlet and outlet openings and a fuel supply nozzle projecting into said chamber, concentric cylinders mounted within said 65 chamber and relatively movable and hav-

ing a wall separating said inlet opening from said outlet opening, one of said cylinders having a cone shaped member provided with a series of air inlet ports communicating with said air intake opening and into which member said fuel supply nozzle projects, said cylinder also having a series of ports communicating with said outlet opening, the other cylinder having ports adapted to register with the ports leading to said outlet opening and provided with means for partially closing said ports, the openings through said partially closed ports corresponding in area to the inlet ports in said member, and means for operating the movable cylinder.

2. A carbureter comprising a casing having a chamber formed therein and inlet and outlet openings therefor, a stationary cylinder mounted within said chamber and having a wall dividing said chamber into independent compartments communicating respectively with said inlet and outlet openings, said cylinder having a cone shaped member formed therein provided with a series of air ports, a fuel supply nozzle projecting into said cone shaped member adjacent to said ports, said cylinder also having a group of air ports above and below said wall, a movable cylinder concentric with said stationary cylinder and also having ports therein communicating respectively with said upper and lower groups of ports and arranged to partially close said upper group of ports and entirely close said lower group of ports, the area of the upper group of ports in said stationary cylinder being equal substantially to the combined area of the ports in said member and said lower group of ports in said stationary cylinder, and means for operating said movable cylinder.

3. A carbureter comprising a casing having a chamber formed therein provided with air inlet and outlet openings and a fuel supply nozzle projecting into said chamber between said inlet and outlet openings, cylinders concentrically mounted within said chamber and relatively movable, a wall separating the space in said chamber around the lower portion of said cylinders from the space in said chamber around the upper portion of said cylinders, one of said cylinders having a central opening into which said nozzle projects and a truncated cone having a closed top encircling said opening within said cylinder, the upper portion of the walls of said cone being provided with a series of ports therein, the ports in the upper portion of said cylinders communicating with the upper part of said chamber and the ports in the lower walls of said cylinders communicating with the lower part of said chamber, means for rotating one of said cylinders and the area of the upper group

of ports in the stationary cylinder being equal substantially to the combined area of the ports in said cone and the lower group of ports in said cylinder.

5 4. A carbureter comprising a casing having a chamber formed therein provided with an air inlet opening in the bottom thereof and an outlet opening in the top thereof, a fuel supply nozzle projecting into said chamber through said inlet opening, cylinders concentrically mounted in said chamber and having groups of ports in their upper and lower walls, the ports of one cylinder registering respectively with the corresponding 15 ports of the other cylinder, said cylinders being mounted for relative rotation to open or close said ports, said chamber being divided into upper and lower compartments, the lower compartment communicating with 20 said inlet opening and with the lower groups of ports, the upper compartment communicating with the upper groups of ports and one of said cylinders having a

member projecting therein and encircling said fuel supply nozzle and having a group 25 of ports above said nozzle and between the groups of ports of said cylinders, substantially as described.

5. A carbureter comprising a casing having inlet and outlet openings and a fuel supply nozzle, concentric relatively movable members mounted within said casing and having groups of ports opened and closed by such relative movement, one of said members having a wall to encircle said 30 nozzle, and provided with a port, the relative movement of said concentric members increasing or decreasing the area of the upper and lower groups of ports, substantially as described. 35

In witness whereof, I have hereunto set my hand this 10th day of December 1913.

JOHN W. STEVENS.
